APPARATUS FOR HANDLING DUST

Frank B. Allen, Lower Marion Township, Montgomery County, Pa., assignor to The Allen-Sherman-Hoff Company, Philadelphia, Pa., a corporation of Pennsylvania

Application December 29, 1942, Serial No. 470,472

3 Claims. (Cl. 302—27)

This invention relates generally to the art of handling finely divided solids and more particularly to means for removing such solids from a plurality of collecting hoppers in steam generating power plants and transporting them to a bulk collection station, a sluiceway or some other place of disposal.

In steam power generating stations, particularly those in which powdered fuel is burned, some of the ash which is carried out of the combustion chamber by the furnace gases is deposited in hoppers before the gases are discharged from the stack. Such ash is finely divided and is difficult to transport from the collecting hoppers to a place of disposal. Various means of handling such finely divided ash, or dust as it will be referred to hereinafter have been proposed. One means used for this purpose is shown in my U.S. Patent No. 1,943,780. Another means is shown in my copending application Ser. No. 464,720 filed November 6, 1942, which is a continuation-in-part of application Ser. No. 429,269 filed February 2, 1942. The present invention is adapted for use with the apparatus shown and described in the aforesaid application.

In the drawings accompanying and forming a part of this specification,

Figure 1 is a top plan view, partly in section, taken on line 1—1 of Fig. 2 and showing one embodiment of the present invention;

Figure 2 is a side elevation, partly in section, of one embodiment of this invention;

Figure 3 is an enlarged plan view, partly in section, taken on line 3—3 of Fig. 2;

Figure 4 is a vertical fragmentary sectional view taken on line 4—4 of Fig. 3;

Figure 5 is an elevational view of the means for rotating the shaft of Figs. 1 and 2;

Figure 6 is a vertical sectional view taken on line 6—6 of Fig. 5;

Figure 7 shows the relative positions of the ratchet and cams on the shaft of Fig. 2 for the two dust valves of that figure;

Figure 8 corresponds to Fig. 7 but shows the arrangement of the ratchet and cams for use with three hoppers similar to the hoppers shown in Fig. 2;

Figure 9 shows an arrangement of the ratchet and cams for four hoppers like those shown in Figure 2.

Figure 10 is a plan view, partly in section, of a modified form of dust valve; and

Figure 11 is a side elevation, partly in section, of the device of Fig. 10.

In Figs. 1 and 2 the two hoppers 1 are each

provided with dust valves 2 like those shown in application Ser. No. 464,720 and presently to be described in some detail. The outlet ends of valves 2 are connected thru branch pipes 3 to a main pipe line 4. A vacuum creating device (not shown) may be used to create a vacuum in pipes 3 and 4 and to cause air to flow thru valves 2 and these pipes, which air will convey dust from valves 2 to any desired place of disposal, for example, a bulk collecting station (not shown) or to a sluiceway (not shown).

Shaft 5, extending along the side of valves 2, is supported in bearing or brackets 6 attached to valves 2, and is supported at one end in a bearing on pedestal 7. This shaft 5 may be made in sections and connected together by piloted, flexible connectors 8. Cams 10 are keyed to shaft 5 adjacent to and engageable with the levers 9 of the several dust valves 2. As each cam rotates it will rotate its lever 9 thru its upstroke and then allow it to move thru its downstroke. These cams 10 are so disposed on the shaft relative to each other that as the shaft is rotated the several cams will so actuate the levers 9 in succession.

In Figs. 1 and 2 the cam of the lefthand valve has actuated the lever to its up position while the lever of the right-hand valve is in its down position. In other words, the cams 10 are so spaced circumferentially around the shaft 5 that the dust valves 2 are individually opened and closed in sequence, one after the other.

Adjacent to the pedestal 7, as is shown in more detail in Figs. 5 and 6, the shaft 5 has a ratchet 11 keyed thereto and a bell crank 12 rotatable thereabout. To the upper arm of this crank is pivoted a pawl 13 and to the lower arm is pivoted a link 14 attached at its lower end to a header 15 carrying depending rods 16 which constitute parts of a thruster.

The thruster shown is a standard device and, as shown, includes mechanism for forcing the rods 16 upwardly and then allowing them to move downwardly thereby causing pawl 13 to rotate ratchet 11 thru a predetermined portion of one complete revolution. The thruster as illustrated, comprises a housing 17 within which is disposed an upper end closure 17a, a hollow cylinder 17b, an annular piston 17c having sliding engagement with the inner surface of housing 17 and with

the outer surface of cylinder 17b, a centrifugal pump designated generally at 17d, and a shaft 17e extending from the pump impeller to the rotor of motor 18 which is supported on the upper end of the thruster housing. Normally, the piston 17c is at the lower end of its stroke in

housing 17, Figures 5 and 6 illustrating the position of the parts 14, 15 and 16 when the piston 17c is at the lower end of its stroke. When the motor 18 is actuated the pump delivers oil or other suitable liquid from within cylinder 17b into the space between the thruster housing 17 and the cylinder 17b and below piston 17c, thereby forcing the piston upwardly in the housing and actuating pawl 13 to rotate ratchet 11. When the piston 17c has reached the upper end of its stroke the motor 18 is de-energized, and the liquid in the space beneath ring 17c may flow thru suitable openings provided therefor (not shown) into the cylinder 17b, with the result that the piston 17c moves slowly down to the bottom end of its stroke, thereby retracting pawl 13 to engage with the next tooth on ratchet 11. It will be understood that the up-stroke of the piston 17c is sufficient in extent to rotate the ratchet 11 thru the desired part of a complete revolution, which part will depend on the number of valves 2 which are controlled by the shaft which is actuated by one thruster.

The arrangement of levers 9, cams 10 and ratchet 11, and the operation of the device shown in Fig. 2, where two dust valves are disclosed, will be better understood by reference to Fig. 7. In the extreme left diagram of that figure the levers 9 of both valves 2 are in their down positions with the cam 10 engaging the lever 9 of the first or lefthand valve of Fig. 2; and the ratchet 11 is shown in its starting position. In the next diagram to the right, the thruster has rotated cam 11 thru 90 degrees, thereby bringing tooth 1 of the ratchet from a horizontal position to a top vertical position and simultaneously rotating the cam 10 of the first valve also thru 90 degrees and thereby actuating lever 9 of the first valve to open position, as shown at the left side of Figs. 1 and 2. The next cycle of the thruster brings tooth 2 of ratchet 11 from a horizontal position to a top vertical position, as shown in the third diagram from the left of Fig. 7, correspondingly rotating cam 10 of the first valve out of engagement with lever 9 of that valve and allowing that lever to resume its down position, and also lifting lever 9 of the second valve to its up position. In the extreme righthand diagram of Fig. 7 the thruster has rotated the ratchet thru 90 degrees from the last described position, thereby permitting lever 9 of the second or righthand valve in Fig. 2 to resume its down position. At such time both levers 9 are in their down position. A subsequent cycle of the thruster is required to bring the cams 10 to the position shown in the lefthand view of Fig. 7 and to position the parts for a repetition of the just described complete cycle.

When there are three dust valves 2 associated with a single shaft 5, the relative positions of the ratchets, cams and levers are shown in Fig. 8, but in view of the foregoing description of Fig. 7 it is believed that no extended description of Fig. 8 is required.

Fig. 9 shows the relative positions of the ratchet teeth, cams and levers for four dust valves which are to be operated in sequence by a single shaft. It will be noted that in Fig. 9 the ratchet 11 has five teeth instead of four as in Figs. 7 and 8, and it will be understood that this is the number of teeth required when there are four cams on the shaft and four levers to be actuated successively by those cams. It is believed that the operation of the apparatus shown in Fig. 9 will

be readily understood from the foregoing description of Fig. 7.

In Figs. 3 and 4 parts of the dust valve 2 are shown in their relationship to shaft 5, lever 9 and cam 10. As above described, the shaft 5 is rotatably carried by bracket 6 adjacent to the outlet end of dust valve 2; and cam 10 is keyed to shaft 5 so as to engage lever 9 of the dust valve. Lever 9 is keyed to shaft 25 which extends at right angles to shaft 5 and is mounted in bearings in valve 2. Within the valve 2 an arm 26 is keyed to shaft 25 and carries a closure element or cover 27 which, in the down position of lever 9, closes the intake end of branch pipe 3. When cam 10 lifts lever 9 to its up position, shaft 25 is rotated and cover 27 is moved to the dotted line position shown in Fig. 4, thereby opening the dust valve to the vacuum existing in branch pipe 3 and permitting the passage of air and dust from the dust valve into pipe 3. When cam 10 passes beyond lever 9 the cover 27 moves by gravity to its pipe closing position shown by the full lines in Fig. 4.

The interior constructions of dust valves 2 are shown completely in my copending application Ser. No. 464,720, but are disclosed in some little detail in the lefthand valve 2 of Fig. 2 and the modifications thereof in Figs. 10 and 11. Briefly described, the valve 2 of Figs. 1 and 2 is provided with an inlet opening opposite branch pipe 3, a horizontal plate 28 at the lower end of the side walls of hopper 1, a rod 30 attached to plate 28 by which the plate may be reciprocated by means outside of the valve (not shown), and dust agitating means 31 pivoted within the hopper which supports plate 28 and permit its reciprocation. The plate 28 is provided with a plurality of holes 29 thru which dust in the hopper may pass into the space below the plate, thru which space a considerable volume of air flows at a high velocity when cover 27 is open. This flow of air entrains the dust in, and falling into, the space below plate 28 and carries such dust thru pipes 3 and 4 to the provided place of disposal.

The modified valve shown in Figs. 10 and 11 is generally similar to the above described valve 2 of Figs. 1 and 2 but differs therefrom in certain particulars. The plate 28 has been omitted and rod 30 has been extended as at 30a, to engage with the lower end of the dust agitating plate which, as indicated at 31a, is narrower than the corresponding plate 31 of Fig. 1. Thus the rod reciprocating means (not shown) serves to actuate the dust agitating means 31a despite the omission of perforated plate 28 of Figs. 1 and 2. Additionally, two tubes 33 are positioned in the lower part of the valve housing and on opposite sides of rod 30a. When the discharge outlet of this modified form of valve is opened and vacuum is applied thereto, air may flow thru and about tubes 33 and entrain and carry away finely divided particles from the housing, as is more fully described in my copending application Ser. No. 464,720.

The operation of the above described apparatus will be understood from the following description. When dust is to be removed from two or more hoppers 1, vacuum is created in pipes 4 and 3, and then the thruster motor is energized and shaft 5 is rotated to lift lever 9 and thereby move cover 27 of the first dust valve to open position, as shown in Fig. 4. At about the same time reciprocation of rod 30 is begun. When all the dust has been removed from the

first hopper, the thruster is again energized to rotate the shaft 5 sufficiently far for the cam 10 to clear the lever 9 of that hopper, thereby allowing the cover 27 to close the outlet from dust valve 2 of that hopper, and to rotate the lever 9 of the next dust valve to its up position, thereby beginning the removal of dust from the second valve.

Having thus described the invention so that others skilled in the art may be able to understand and practice the same, I state that what I desire to secure by Letters Patent is defined in what is claimed.

What is claimed is:

1. Dust handling apparatus comprising a plurality of housings, each housing communicating with the discharge opening of a dust collecting hopper and having an inlet for air and an outlet for air and dust, and a pivoted closure in the housing for its outlet, a conduit operatively associated with said outlets and with means for creating a partial vacuum therein, a shaft rotatable in only one direction and through successive steps of not more than 90° each to operate said closures in succession, and cooperating means operatively associated with said shaft and with each of said closures to pivot one closure to open position when the shaft is rotated through one of said steps and to permit movement of that closure to closed position before initiation of the opening movement of the closure of another housing.

2. Dust handling apparatus comprising a plurality of housings, each housing communicating with the discharge opening of a dust collecting hopper and having an inlet for air and an outlet for air and dust, and a pivoted closure in the housing for its outlet, a conduit operatively as-

sociated with said outlets and with means for creating a partial vacuum therein, a shaft rotatable in only one direction and through successive steps of not more than 90° each to operate said closures in succession, cooperating means operatively associated with said shaft and with each of said closures to pivot one closure to open position when the shaft is rotated through one of said steps and to permit movement of that closure to closed position before initiation of the opening movement of the closure of another housing, and means to rotate said shaft step-wise comprising a ratchet on the shaft, a reciprocable pawl engageable with said ratchet, and means to reciprocate said pawl.

3. Dust handling apparatus comprising a plurality of housings, each housing communicating with the discharge opening of a dust collecting hopper and having an inlet for air and an outlet for air and dust, a closure in the housing for its outlet, a shaft extending through the housing and operatively attached to said closure and an arm on the shaft outside of said housing, a conduit operatively associated with said outlets and with means for creating a partial vacuum therein, a shaft rotatable in only one direction and through successive steps of not more than 90° to operate said closures in succession, said shaft having cams thereon engageable with said arms, the arm and cam of one housing serving to move the closure of that housing to opened position during one step of rotation of the cam carrying shaft and to permit movement of that closure to closed position prior to initiation of the opening movement of the closure of another housing.

FRANK B. ALLEN.
